United States Patent Office

Des. 219,358
Patented Dec. 1, 1970

219,358

FOOD CUTTING MACHINE

Samuel J. Popeil and Raymond Popeil, Chicago, Ill.,
assignors to Popeil Brothers, Inc., Chicago, Ill., a cor-
poration of Delaware

Filed Dec. 17, 1969, Ser. No. 20,531

Term of patent 14 years

Int. Cl. D15—12

U.S. Cl. D89—1

FIG. 1

FIG. 2

FIG. 3

FIG. 4

FIG. 5

FIG. 6

FIG. 1 is a front perspective view of a food cutting machine showing our new design;

FIG. 2 is a rear perspective view;

FIG. 3 is a front elevational view;

FIG. 4 is a right side elevational view;

FIG. 5 is a rear elevational view; and

FIG. 6 is a top plan view.

The handle is shown fragmentarily in FIGS. 4 and 6 for convenience of illustration.

We claim:

The ornamental design for a food cutting machine, as shown and described.
